(57) **CLAIM**

The ornamental design for a hammer handle, as shown and described.

DESCRIPTION

FIG. 1 is a top perspective view of a hammer with a handle according to a first embodiment of my new design.

FIG. 2 is a right side view thereof.

FIG. 3 is a rear view thereof.

FIG. 4 is a front view thereof.

FIG. 5 is a top view thereof.

FIG. 6 is a bottom view thereof.

FIG. 7 is a left side view thereof.

FIG. 8 is a right side view thereof showing the handle in isolation.

FIG. 9 is top perspective view of a hammer with a handle according to a second embodiment of my new design.

FIG. 10 is a right side view thereof.

FIG. 11 is a rear view thereof.

FIG. 12 is a front view thereof.

FIG. 13 is a top view thereof.

FIG. 14 is a bottom thereof.

FIG. 15 is a left side view thereof; and,

FIG. 16 is a right side view thereof showing the handle in isolation.

The broken line showings of the hammer heads are provided for purposes of environment and form no part of the claimed design.
